UNITED STATES PATENT OFFICE.

FRANKLIN W. KELLY, OF VERNONTVILLE, MICHIGAN, ASSIGNOR TO HIMSELF AND ELVIN U. STILES, OF SAME PLACE.

CAR-COUPING.

SPECIFICATION forming part of Letters Patent No. 268,905, dated December 12, 1882.

Application filed April 24, 1882. (Model.)

To all whom it may concern:

Be it known that I, FRANKLIN W. KELLY, of VERNONTVILLE, in the county of Eaton and State of Michigan, have invented a new and Improved Car-Coupling, of which the following is a full, clear, and exact description.

The invention consists in a U-shaped rod passed through the bottom of the draw-head into the cavity, on the cross-piece of which U-shaped rod an eye is loosely mounted, to which eye a lever is pivoted, which is also pivoted to the draw-head or a projection of the same, whereby the U-shaped rod will raise the link in the cavity in the draw-head by pulling this lever downward.

Reference is to be had to the accompanying drawings, forming part of this specification, in which similar letters of reference indicate corresponding parts in all the figures.

Figure 1 is a plan view of my improved car-coupling. Fig. 2 is a longitudinal sectional elevation of the same. Fig. 3 is an end elevation of the same.

The draw-head A is provided with a cavity, B, open at the front and top, the bottom of this cavity being inclined from the inner to the outer end, as shown in Fig. 2. At the inner end of the cavity a recess, C, is formed, above which a tongue, D, projects, which tongue extends transversely across the cavity B. A longitudinal ridge, E, projects upward from the bottom of the cavity B in such a manner that this ridge will be free on all sides—that is, there will be a space between this ridge and the sides of the draw-head. A curved recess, F, is formed in the upper front or outer corner of the ridge E, and the front edge of the ridge is slightly rounded or beveled. The link G is provided with a middle cross-piece, H. A U-shaped rod, J, passes through the bottom of the draw-head into the cavity, one shank of the U-shaped rod being at each side of the ridge E. The bottom cross-piece of the U-shaped rod J passes through a loop, K, pivoted to the lower end of a curved or bent lever, L, pivoted to the draw-head or to a short arm, M, projecting from the bottom of the draw-head at one side.

The operation is as follows: If the cars are to be coupled, the inner end of the link G is

passed into the recess C under the tongue D, and the cross-rod H of the link is placed in the recess F, so that the link will be held inclined upward and outward from the draw-head. If the two draw-heads come in contact, the shock throws the link over the ridge E of the disengaged draw-head, and the cars will be coupled, as the ridges of both draw-heads will pass through the link G, as shown in Fig. 1. If the cars are to be uncoupled, the lever L of one of the draw-heads is drawn down in the direction of the arrow a', whereby the U-shaped rod J will be raised into the cavity, and will push upward or raise the link to clear the ridge of the draw-head in which the link is raised. The lever L can be operated by means of a hook, or by means of a lever pivoted to the same and reaching to the side of the car. By means of my improved coupling the cars can be coupled automatically, and can be uncoupled without requiring the operator to pass in between the cars. Cars provided with my improved coupling can be coupled to cars provided with the usual link-and-pin coupling.

Having thus fully described my invention, what I claim as new, and desire to secure by Letters Patent, is—

1. The combination, with the draw-head A, provided with the cavity B, and the ridge E, of the U-shaped rod J, projecting through the bottom of the draw-head into the cavity, and adapted to bear directly against the link on opposite sides thereof when raised by a lever, L, to disengage the link from the ridge in uncoupling, substantially as described.

2. The combination, with the draw-head A, constructed with a cavity, B, and a ridge, E, projecting upward from the bottom of the cavity, of the U-shaped rod J, projecting through the bottom of the draw-head into the cavity, the eye K, loosely mounted on the cross-pieces of the rod J, and the lever L, pivoted to this eye K and to the draw-head or a projection of the same, substantially as herein shown and described, and for the purpose set forth.

FRANKLIN W. KELLY.
